6 Claims. (Cl. 250—36)

1

This invention relates in general to magnetrons and more particularly to means for stabilizing the operating frequency thereof, especially with regard to plural cavity magnetrons.

The conditions which affect the magnetron operating frequency include load conditions, temperature of the magnetron elements, and "pushing."

The effect of load conditions on magnetron operating frequency may be expressed in terms of the pulling figure (see *Microwave Magnetrons*, Collins, pp. 182-3, 642-3, 770-1). One definition for pulling figure is the value of the maximum change of frequency experienced by a magnetron feeding an output line having a voltage standing wave ratio of 1.5 due to a change in load impedance sufficient to shift the standing wave 360 electrical degrees along the line. Reduction in pulling figure may be obtained by decoupling the output line from the magnetron to a greater extent. This procedure is undesirable in that the circuit efficiency is reduced in this operation and, further, that the electronic efficiency of the magnetron falls off as the load is reduced.

The effect of temperature on magnetron operating frequency is ordinarily given by multiplying the magnetron frequency by the coefficient of thermal expansion of the material of which the magnetron resonant members are constructed, the result being, say, the number of megacycles per degree of temperature shift. The severity with which the pulling figure affects the magnetron frequency as compared to the effect of temperature depends in the main on the operating frequency.

"Pushing," which is the effect of the parameters within the magnetron on the operating frequency, depends upon the individual magnetron. In general, the effect of "pushing" is quite small with respect to the effects of pulling and temperature change.

Another difficulty encountered in keeping a magnetron at a predetermined operating frequency is the tendency for such a tube to oscillate in other modes than the desired one. That is, due to the large number of degrees of freedom that a plural cavity magnetron possess, it is possible for the electric and magnetic fields within the cathode-anode space to assume several different configurations. Each of these field patterns corresponds to a different frequency of oscillation of the magnetron. These configurations are called modes of oscillation or, more simply, modes.

The term stabilization, as used in connection with magnetron operation, refers to improve-

2

ments in frequency constancy with regard to changes in operating conditions. Any magnetron is stable to some degree because there is associated with it a resonant circuit which stores electrical energy at its resonant frequency. It can be shown that the degree to which a system tends to operate near this frequency is a function of the amount of energy stored in the resonant circuit. Improvements of frequency constancy, therefore, may be looked for from a device which stores additional energy at the desired frequency of operation. With regard to the type of magnetron having its anode structure comprising a number of cavity resonators, which shall be called a plural cavity magnetron, the device usually takes the form of a resonant cavity coupled in some manner to the circuit of the magnetron.

In the discussion of stabilization, it is convenient to define the stabilization factor S:

$$S = \frac{\text{total energy stored in system}}{\text{energy stored in unaltered magnetron}}$$

That frequency changes due to varying operating conditions are reduced by this factor (provided the frequency of the stabilizing cavity is not affected by these changes) can be seen from Equation 2 in the book by E. A. Guillemin entitled "Communication Networks," volume II, page 229, and the explanation connected therewith.

30 Among the objects of the present invention, therefore, are:

1. To provide a magnetron oscillator for use at extremely high frequencies;
2. To provide such an output circuit for this magnetron that a high degree of stabilization may be obtained; and
3. To provide means in the output circuit for lessening the effects of undesirable modes of oscillation of the magnetron.

40 In accordance with the present invention there is provided a plural cavity magnetron which is tightly coupled to a high-Q cavity resonator through a wave guide, the cavity being connected to the branch line of a wave guide T-junction.

45 A dissipative load consisting of a length of a post of powdered iron dispersed in a ceramic, which substance will be referred to as polyiron, is placed substantially parallel to the electric field in the wave guide and off center therefrom in the branch wave guide. A capacitive conducting post is

50 placed adjacent to the polyiron post to balance out the susceptance effects thereof. This polyiron post is so placed that undesired modes of the magnetron will be appreciably loaded down by it, so that these modes have extreme difficulty

building up. The desired mode, however, will be virtually unaffected.

A "line stretcher" is placed in the main wave guide, to which the magnetron is coupled, to correct for small variances in the effective length of the line connecting the magnetron and the cavity resonator which may occur during manufacture. In order not to load the magnetron too heavily, a capacitive screw is placed in the portion of the main wave guide to which the load is connected, in order to increase the mismatch looking toward the load at this point. The "line stretcher," capacitive screw and inductive post are more fully explained later in this specification.

This invention will best be understood by reference to the drawings, in which:

Fig. 1 is an illustration of the magnetron and stabilization means according to the present invention; and

Fig. 2 is an approximate equivalent circuit diagram of the device of Fig. 1.

Fig. 3 is a diagrammatic section in plan, of the wave guide T-section and stabilizing cavity resonator taken on the line B—B Fig. 4.

Fig. 4 is a diagrammatic section of the main wave guide and magnetron anode block in elevation, taken along the line A—A Fig. 3.

Fig. 5 is a sectional view of the main wave guide 14 taken through elements 17 and 18 on the line D—D Fig. 3.

Fig. 6 is a sectional view of the branch wave guide 20 taken through elements 22 and 23 on the line C—C Fig. 3.

Referring now to a description of the invention and to the drawings, Fig. 1 shows a plural cavity magnetron 10 of a type of construction sometimes called the "bathtub" construction, because of the shape of the magnetron case (see Microwave Magnetrons, Collins, pages 770-1, Figs. 19.37 and 19.38). The resonant cavities are positioned substantially symmetrically with respect to the bathtub-shaped outer case of the magnetron unit, with the long axes of the cavities being essentially perpendicular to the long face 11 of the case as indicated diagrammatically at 41, Fig. 4. The two cathode leads, not shown, are brought into the magnetron through the unit 12. The magnetron output is coupled to one of the cavity resonators by a coupling loop 49 Fig. 4 formed from the center conductor 43 of a coaxial line 13 which passes through the anode block 42 of the magnetron, the outer conductor 13 of which may be seen in Fig. 1. This output energy is in turn coupled into a wave guide 14 by causing the center conductor 43 of the coaxial line to extend beyond the outer conductor 13 and to form a probe 44 Fig. 5, which is positioned substantially parallel to the electric field E Fig. 4 inside the wave guide, the guide preferably operating in the TE₀₁ mode. The electric field is thus substantially parallel to one end plate 19 of the guide. Two permanent magnet pole pieces 15 and 16 are shown providing the longitudinal magnetic field necessary for the operation of the magnetron.

The susceptance looking into the wave guide 14 from the output end 27 as shown in Fig. 6 is made variable by inserting an inductive conducting post 17 and a capacitive tuning screw 18 inside the guide 14 and at essentially the same cross section therein. The post 17 is a small diameter conducting post which is firmly welded to the top and to the bottom of the wave guide 14, and whose axis is substantially parallel to the elec-

tric field inside the guide. The screw 18 makes very good contact with the top of the guide, and the distance of the bottom face of the screw from the bottom wall of the guide may be varied by turning the screw.

The function of the conducting post 17 is to create an increased effective inductance at the point in the wave guide at which the post is placed. Currents flow through such a post from one plate of the wave guide to the other, thus affecting the main magnetic field in the guide, which field is substantially perpendicular to the post, in such a manner that the effective inductance at this point is increased.

The function of the screw 18 is to create an increased effective capacitance at the point in the wave guide at which the screw is placed. The effect is to increase the electric field in the guide at this point due to the shortening of the electric lines, thus increasing the effective capacitance.

A branch wave guide 20 couples the main wave guide to a high-Q cavity resonator 21 by means of a wave guide T-junction, the effective length of line from the magnetron to the cavity resonator being made substantially equal to an integral number of half wavelengths at the operating frequency of the system. The branch guide 20 is butted against the main guide 14 in such a manner that corresponding faces of both guides are substantially parallel. The coupling hole cut in the side of the main guide 14 is of the same area as the area of the inside of a section cut perpendicular to the long axis of the branch guide 20. A large wave guide iris, 45 Figs. 3 and 4, couples the branch guide 20 to the stabilizing cavity resonator 21. An iris is a small hole through which the electromagnetic energy must pass, the geometry of the hole determining the magnitude and phase angle of the effective impedance presented by the iris. The load 22 which damps out the undesirable modes is placed in the branch wave guide 20. This load 22 is a post of material of powdered iron dispersed in a ceramic. When used for dissipating high-frequency electromagnetic energy in this manner, this substance is called polyiron. This post 22 is placed off center in the guide 20 substantially parallel to the electric field therein, and is firmly connected to the top and the bottom of the guide. Along the same cross section of the branch guide as the polyiron post 22 is a conducting capacitive post 23, which is connected to either the top or the bottom of the guide and extends a portion of the way between top and bottom. An arrangement for varying the volume of the cavity resonator 21, and thus its resonant frequency, is by means of a rod 25 and screw 26, which is made to vary the position of the end 24 of the cavity.

The output of the system is taken from the end 27 of the main wave guide 14. A capacitive screw 28, similar to screw 18, is placed in the main wave guide in substantially the position shown.

An approximate equivalent circuit diagram of the apparatus of Fig. 1 is shown in Fig. 2. The magnetron is represented here as a parallel resonant circuit consisting of inductance 30 and capacitance 31. The wave guide line connecting the cavity resonator and the magnetron is represented here as a series resonant circuit of variable capacitance 32 and inductance 33, the line being substantially an integral number of half-wavelengths long. The resistance 34 represents the effect of the polyiron post 22. The stabilizing cavity resonator is represented by the parallel resonant circuit of inductance 35 and capacitance

36. The system load is represented as resistance 37, with the capacitance 38 being the approximate equivalent of the capacitive screw 28.

Referring now to the operation of the circuit, the magnetron used here must be a comparatively low voltage, low power tube. It is desirable that in the equivalent circuit diagram of Fig. 2, when the magnetron is operating at frequency f_0 the cavity resonator be tuned to f_0 , and the length of the line connecting the magnetron and the cavity be an integral number of half-wavelengths at the frequency f_0 . The desired mode f_0 , therefore, causes the line to act as a comparatively small impedance and the cavity to act as a comparatively large impedance, both of these impedances being resistances under hypothetical ideal operating conditions. Since the resistance of the dissipative load 34 is small compared to the impedance offered by the cavity at resonance, very little voltage is available across the load 34 to dissipate energy therein, and a large amount of the power leaving the magnetron is coupled to the main load 37, this power being cut down somewhat by the deliberate mismatch caused by capacitance 38. It can furthermore be seen that the magnetron may be tuned by varying the resonant frequency of the cavity.

Electromagnetic waves of a frequency differing from f_0 cause the wave guide line to act as a higher impedance than in the previous case, and cause the cavity resonator to act as a lower impedance. There is thus a lower value of voltage built up across the branch containing load 37, and of this voltage, a comparatively large fraction appears across the dissipative load 34. This undesired mode therefore is loaded down, or damped, by the polyiron post 22. The reason this stabilizing means can be applied only to comparatively low power magnetrons is that the dissipative elements are positioned within the wave guide, thus allowing only a limited amount of heat dissipation due to the confined space present.

The output coupling loop 40 of the magnetron is made comparatively large, in order that the coupling to the cavity resonator be tight. The lengths of the branch wave guide 20 and the main wave guide 14 to the T-junction are such that the load is coupled to a point in the wave guide where the cavity resonator and magnetron appear as effective parallel resonant circuits in parallel.

The lossy polyiron element is placed at a voltage minimum or nodal point for optimum effect. The polyiron post 22 presents an inductive susceptance to the energy flow down the branch guide 20, so a capacitive susceptance conducting post 23 is used at the same cross section to balance out this inductive susceptance. Since the polyiron is in the role of a conductance across the wave guide, it is placed in a position where the magnetron and cavity appear as series resonant circuits in series to provide the proper mode damping action. This position is substantially a quarter-wave-length from the T-junction.

It is desirable to tightly couple the stabilizing cavity to the magnetron so that the former has the optimum effect, but this tends to load down the magnetron considerably. The capacitive screw 28 therefore, which acts as a load step-down transformer, is necessary in order not to load down the magnetron too heavily. At the same time, use is made of this tuning screw to balance out an undesirable susceptance characteristic of the T-junction.

Due to variances in magnetron production, it 75 tive post positioned in said wave guide, and a

is difficult to predict the effective length of the line connecting the magnetron and the cavity when the two are assembled in the apparatus. To cancel out these effective line length changes which may occur, the line length compensating susceptances 17 and 18 are used. The inductive post 17 is fixed, and the geometry of the capacitive screw 18 is such that inductive and capacitive resultant susceptances may be provided over the range of the turning of the screw 18. Since a change in line length results in a change in the value and phase of the susceptance the line presents to the circuits coupled thereto, this variable susceptance unit is a means of varying the effective line length. It is sometimes called a "line stretcher."

Thus there is provided a highly flexible stabilized magnetron for low power use. It is to be understood that this invention is not limited to use with the type of magnetron or to the design of circuit shown. It may be applied to any type of low power magnetron, the only limitation on the circuit design being that the apparatus adheres to the basic principles set forth.

25 While there has been described what is at present considered the preferred embodiment of the invention, it will be obvious to those skilled in the art that various changes and modifications may be made therein without departing from the invention, and it is, therefore, aimed in the appended claims to cover all such changes and modifications as fall within the true spirit and scope of the invention.

What is claimed is:

35. A stabilized magnetron circuit comprising a plural cavity magnetron, a variable frequency stabilizing cavity resonator a wave guide T-junction section closed at one end connecting said cavity magnetron to said cavity resonator, a coaxial line connecting one of the cavities of said magnetron to the closed end of said wave guide, probe, probe iris means connecting said stabilizing cavity resonator to a branch of said wave guide T-junction, a polyiron energy absorbing post positioned unsymmetrically in said branch guide a capacitive conducting post positioned in substantially the same cross sectional plane of said branch guide as said polyiron post for substantially balancing out the inductive susceptance of polyiron post, said cross sectional plane positioned at a positioned node at normal frequency whereby said polyiron rod absorbs electromagnetic energy of frequencies differing from the operating frequency of said magnetron, a variable impedance positioned in said main wave guide comprising a conducting inductive post and a first capacitive variable screw in substantially the same cross sectional plane of the wave guide as said inductive post, and a second 55 capacitive variable screw placed in the output end of said main wave guide to provide a mismatch in the wave guide beyond the branch of said T-junction.
60. A stabilized magnetron circuit comprising a plural cavity magnetron, a cavity resonator, a wave guide connecting said magnetron to said cavity resonator, a polyiron energy absorbing post mounted at a potential node at the operating frequency in said wave guide, a capacitive conducting post positioned in substantially the same cross sectional plane in said wave guide as said polyiron post for effectively cancelling out the inductive susceptance of said polyiron post, a variable impedance comprising an inductive

65. A stabilized magnetron circuit comprising a plural cavity magnetron, a cavity resonator, a wave guide connecting said magnetron to said cavity resonator, a polyiron energy absorbing post mounted at a potential node at the operating frequency in said wave guide, a capacitive conducting post positioned in substantially the same cross sectional plane in said wave guide as said polyiron post for effectively cancelling out the inductive susceptance of said polyiron post, a variable impedance comprising an inductive
70. A stabilized magnetron circuit comprising a plural cavity magnetron, a cavity resonator, a wave guide connecting said magnetron to said cavity resonator, a polyiron energy absorbing post mounted at a potential node at the operating frequency in said wave guide, a capacitive conducting post positioned in substantially the same cross sectional plane in said wave guide as said polyiron post for effectively cancelling out the inductive susceptance of said polyiron post, a variable impedance comprising an inductive

capacitive variable screw positioned in substantially the same cross sectional plane in said wave guide as said inductive post, and wave guide means for coupling the output of said magnetron circuit into a load.

3. A stabilized magnetron circuit comprising a plural cavity magnetron, a cavity resonator, a wave guide connecting said magnetron to said cavity resonator, a polyiron dissipative element mounted in said wave guide at a potential node at operating frequency, whereby said polyiron dissipative element absorbs electromagnetic energy of frequencies differing from the operating frequency of said magnetron, and wave guide means for coupling the output of said magnetron circuit into a load.

4. A stabilized magnetron circuit comprising a plural cavity magnetron, a cavity resonator, a wave guide connecting said magnetron to said cavity resonator, dissipative load means mounted at a potential node in said wave guide connection to said cavity resonator, whereby said dissipative load partially absorbs electromagnetic energy of frequencies differing from the operating frequency of said magnetron, and wave guide means for coupling the output of said magnetron circuit into a load.

5. A stabilized vacuum tube oscillator circuit comprising a vacuum tube oscillator, a cavity resonator, a wave guide connecting said oscillator to said cavity resonator, dissipative load means mounted at a potential node in said wave

guide connection to said cavity resonator, whereby said dissipative load partially absorbs electromagnetic energy of frequencies differing from the operating frequency of said oscillator, and wave guide means for coupling the output of said oscillator circuit into a load.

6. A stabilized magnetron circuit comprising a magnetron, a cavity resonator with a wave guide connection having a potential node constituting an effective parallel resonant circuit, an energy dissipative means located at said node, a wave guide connecting said magnetron to said effective parallel resonant circuit, whereby said dissipative means absorbs electromagnetic energy associated with frequencies differing from the operating frequency of said magnetron, and wave guide transmission means for coupling the output of said magnetron circuit into a load.
